ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed November 15, 1923. Serial No. 674,923.

My invention relates to electric switches, and particularly to switches of the push through type. The object of my invention is to provide a simple and efficient switch mechanism of this character, having an improved snap action, together with an appropriate insulating body on which the mechanism and associated contacts are mounted.

10 In the accompanying drawings—

Fig. 1 is a side elevation of a lamp socket in which my invention is embodied in one form;

15 Fig. 2 is a broken vertical section there- through;

Fig. 3 is a similar view of the insulating base of the socket showing the switch mech- anism in a different position;

Fig. 4 is a section on the line 4—4, Fig. 3;

20 Fig. 5 is a broken plan view of the socket;

Fig. 6 is an inverted plan view of the upper button of the socket body showing portion of the switch mechanism in position thereon;

25 Fig. 7 is a plan view of the other button of the socket body showing the switch spring seated therein;

Fig. 8 is a perspective of the switch frame and associated elements;

30 Fig. 9 is a broken side elevation of a lamp socket in which my invention is embodied in modified form;

Fig. 10 is an inverted plan view thereof;

Fig. 11 is a section on the line 11—11,

35 Fig. 1;

Fig. 12 is a similar view showing the switch mechanism in different position;

Fig. 13 is a section on the line 13—13, Fig. 12;

40 Figs. 14 and 15 are perspective views of details; and

Fig. 16 is a perspective of the switch frame.

While I have illustrated my invention in an electric lamp socket, it will be understood that the switch mechanism is applicable to fittings of various other types. It will further be recognized that the details of construction are subject to many variations other than those shown in the modifications illustrated, and that what I claim as my invention is not restricted to the particular embodiments shown and described.

45 In the construction illustrated in Figs. 1 to 8, the invention is applied to an electric

lamp socket comprising an insulating base formed by two buttons 20 and 21 of any suitable insulating material, such as porcelain, one or both suitably recessed on their meeting faces to form a switch chamber, and one or both buttons transversely channelled to afford a passageway for the operating push bar 22 and its associated finger pieces 23 and 24. Mounted on the button 21 is a screw shell 25 for the reception of a lamp base, or the like, the base flange 26 of the screw shell being engaged by the yoke 27 integral with the offset terminal lug 28 which projects through the base flange 26 of the screw shell into a wiring channel 29 in which is housed the binding screw 30. The center contact 31 of the socket is secured by screw 32 or the like, to the button 21, and its base is offset to form a fixed switch contact 33 which enters, and lies against one wall of, the passage 34 formed in the button 21 to accommodate and permit play of the switch bar rocker 35 which makes and breaks connection with the switch contact 33.

The rocker 35 is pivoted at 36 on the push bar 22 and moves with the latter on its longitudinal displacement in the frame 37. The latter is here shown formed of sheet metal, from the web of which are offset in one direction parallel arms 38 and 39 and an intermediate arm 40 offset in opposite direction, the several arms engaging in appropriate channels in the buttons 21 and 20 which thus accurately locate the frame and hold the same in position with respect to the base. The arm 39 is extended out of the switch chamber and is provided with an offset wire terminal end 41 extending into channel 42 in which the binding screw 43 is housed.

Underlying the arms 38 and 39 of the switch frame is the base 44 of the flat metal switch spring, the spring arm 45 of which is bent up from the base and terminates in a gabled head having opposite inclines 46 and 47 which in the adjusted position of the parts underlie the cam end 48 of the rocker 35. The cam end 48 of rocker 35 rides the gable inclines 46 and 47 of the spring and the rocker is thrown thereby with a snap action.

The operation of the switch will be readily understood from Figs. 2 and 3. In Fig. 2 the rocker is shown in circuit-closing position, in which one side α of the cam end 48

thereof bears against the incline 47 of the switch spring, the effort of which maintains the opposite end of the rocker in engagement with the contact 33. Electrical connection 5 between the wire terminal end 41 of the frame and the center contact 31 of the socket is thus established through the frame, push bar and rocker. When the push bar 22 is shifted to the left by pressure on the finger 10 piece 24, the rocker 35 is bodily moved therewith. Its angular position with respect to the push bar is changed, however, by reason of the engagement of one end of the rocker with the contact 33, while the push bar is 15 shifted. The cam nose 48 of the rocker therefore rides up the incline 47 of the spring arm 45, increasing the stress of the latter by reason of its depression. As the cam nose of the rocker passes the crest 49 of the spring 20 arm, the incline 46 of the latter exerts its effort against the opposite side γ of the cam nose 48 and throws the rocker with snap action away from the contact 33, thus interrupting the electrical connection therewith. 25 When it is desired to again complete the connection between the rocker and the contact 33, the push bar 22 is shifted to the right by pressure on the finger piece 23. The rocker 35 is again shifted bodily with the bar 22, 30 but its contact end is now engaged with the arm 39 of the frame. Consequently, as the bar 22 is shifted to the right, the rocker 35 changes its angular position, the contact end thereof sliding upward toward the contact 35 33. This movement causes the nose of the cam end thereof to ride up the incline 46 of the spring arm, again stressing the latter by depression, and crossing the crest 49 as the contact end of the rocker approaches the 40 contact 33. As the cam nose passes the crest, the rocker is swung with snap action by the rise of the spring, its incline 47 now engaging the opposite side of the cam nose of the rocker. 45 In the construction shown in Figs. 9 to 16 inclusive, the essential features of operation are retained, the details of construction being somewhat modified. In this form the two-button insulating base is replaced by a 50 single porcelain button 50 deeply channelled at 51 for the reception of the switch mechanism and push bar 52. The screw shell 53 is supported upon the base by means of a yoke 54 which overlies the base flange 55 and 55 carries the wire terminal strap 56. Overlying the yoke 54 is a disc of insulating fiber, or the like, 57, to which is riveted the base 58 of the center contact 59. Extending from the base 58 is a combined switch contact and spring 60, which passes around one margin of the disc 57 and projects into the switch chamber 51. The center contact and screw shell are mounted upon the button 50 by the screws 61 which pass through and button 50 on opposite sides of the channel 51 and take

into the tapped bosses 62 formed in the base 58 of the center contact 59.

The switch frame 63 is provided with a pair of side webs 64 and 65, through which the push bar 52 passes, and by which it is 70 guided. A base lug 66 on the frame is tapped to receive the screw 67 by which it is secured to the button 50. The rocker 68 is pivoted at 69 to the push bar 52 and is provided with a cam nose 70 which, in the adjusted position of the parts, bears against the spring arm 60 and rides the inclines 71 and 72 thereof at opposite sides of the crest 73 in a manner analogous to that described in the foregoing construction. 80

The contact end of the rocker 68 plays in a recess 74 in the button 50. Against one wall of the recess lies the contact 75 formed by the offset end of the binding screw strap 76 which is secured by the screw 77 to one end of the base. A washer 78 of insulating material, such as fiber, is forced into a seat 79 surrounding the passage 74 and serves to exclude dirt and dust from the region of the 90 cooperating contacts.

The operation of this mechanism is substantially like that first described. In Fig. 11 the switch is shown in circuit-closing position, the connection between the wire terminal contact 75 and the center contact spring 60 being established through the rocker 68. To break the connection between these parts, the push bar 52 is shifted to the left, moving the rocker 68 therewith, and causing its cam nose 70 to pass over the crest 73 of the spring 60, which thereupon swings the rocker with a snap action to the open-circuit position indicated in Fig. 4, in which the contact end of the rocker rests against the stop face 80 of the recess 74. When it is desired to establish the circuit again, the push bar is shifted in the opposite direction, thus causing the contact end of the rocker to slide on the surface 80 until the cam nose 70 thereof passes the crest 73 of the spring 60, whereupon the incline 72 of the spring arm bearing on the opposite side of the cam nose throws the rocker against the fixed contact 75 and maintains the same in engagement therewith. 100

In the construction just described, the rocker affords a direct connection between the center contact and the wire terminal contact, as distinguished from that first described, in which the connection is effected through the switch frame and push bar. In the latter case, however, the engagement between the moving parts and the frame is sufficiently maintained by the pressure of the spring to insure good electrical connection. 110

It will be noted that in both constructions the support of the rocker on the push bar is effected by an integral boss struck from the push bar and taking into a bearing aper-

ture in the rocker. The rocker is held on the boss by its confinement between the push bar and the web of the frame. To receive the bar, the arms 38-39 or 64-65 of the frame 5 are slotted and the metal 81 adjacent the slot peened over (see Fig. 4) the bar to detain it after assembly. The enlarged area of the bar between the guide arms affords shoulders 10 82 which form stops limiting the play of the bar in the frame.

Both of the constructions illustrated are readily formed and assembled. The spring 15 operation of the rocker causes the snap movement of the switch bar to open-circuit position, and the constant spring engagement with the rocker insures its maintenance in both "on" and "off" positions. A wide break is attained, sufficient to properly handle a commercial lighting circuit of the usual voltage.

With the understanding that various modifications may be made in the construction which do not depart from what I claim as my invention, I claim—

25 1. In an electric switch, a push bar having a rectilinear movement, an inflexible rocker pivoted on said push bar and bodily movable therewith, together with a spring having a sliding engagement with said rocker and operative to oscillate the latter with a snap action after a predetermined bodily movement of the rocker by the push bar.

30 2. In an electric switch, a push bar having a rectilinear movement, an inflexible rocker pivoted intermediate its ends on said push bar, one end of said rocker having a cam nose, and a gabled spring engaging said cam nose of the rocker and serving to throw the latter with a snap action on the movement 35 40 of the rocker nose across the crest of the gable by the rectilinear displacement of the push bar.

3. In an electric switch, a push bar having a rectilinear movement, a rocker pivoted thereon and bodily movable therewith, fixed means engaged by said rocker at opposite ends of its throw and serving to change the angular position of the rocker with respect to the push bar on displacement of the latter, together with spring means having a 45 50 55 sliding engagement with the rocker and serving to complete with a snap action the throw of the rocker initiated by the displacement of the push bar.

4. In an electric switch, a push bar having a rectilinear movement, a rocker pivoted thereon and bodily movable therewith, fixed means engaged by said rocker at opposite ends of its throw and causing one end of the rocker to move in a general direction opposed to that of the push bar on displacement of the latter, together with spring means having a sliding engagement with the rocker and serving to complete with a snap action the throw of the rocker initiated by 60 65 the displacement of the push bar.

5. In an electric switch, a push bar having a rectilinear movement, a frame having spaced supports in which said bar slides, and a web parallel to the push bar, together with 70 a rocker pivoted on said push bar and arranged between the latter and the frame web.

6. In an electric switch, a push bar having a rectilinear movement, a frame having spaced supports in which said bar slides, and a web parallel to the push bar, together with a rocker pivoted on said push bar and arranged between the latter and the frame web, said web serving to retain the rocker in 75 80 pivoted engagement with the push bar.

In testimony whereof I have signed my name to this specification.

ARVID H. NERO.
